UNITED STATES PATENT OFFICE.

WILLIAM D. BULLOCK, OF PROVIDENCE, RHODE ISLAND.

DRAW-BRIDGE.

SPECIFICATION forming part of Letters Patent No. 322,787, dated July 21, 1885.

Application filed May 26, 1885. (No model.)

To all whom it may concern:

Be it known that I, WILLIAM D. BULLOCK, of the city and county of Providence and State of Rhode Island, have invented a new and useful Improvement in Draw-Bridges, of which the following is a full, clear, and exact description, reference being had to the accompanying drawings, which form a part of this specification.

10 My invention relates to swinging and draw bridges; and the object of my invention is to produce an intermittent connection for operating gates or signals upon the fixed spans by power applied from the center of the draw.

15 To the above purpose my invention consists in certain peculiar and novel features of construction and arrangement, as hereinafter described and claimed, whereby signals, gates, &c., upon the fixed or shore spans are operated directly from the center of the draw, thus avoiding all interference or delay in the operation of the draw, and also avoiding additional assistance in working the gates or signals and the loss of time due to the keeper having to travel back and forth upon the draw

25 to operate the gates or signals.

In order that my invention may be fully understood I will proceed to describe it with reference to the accompanying drawings, in

30 which—

Figure 1 is a side elevation of the meeting ends of a shore-span and the draw with my improvement applied. Fig. 2 is an end elevation of the shore-span with its operative attachments. Fig. 3 is a similar view of the draw with its operative attachments.

35 In the said drawings, A designates the draw, and B the fixed span. Upon the outer end of the draw A are mounted two vertical guides, C, supported parallel with each other by a frame, D. Upon the frame D is mounted a grooved pulley, E, over which runs a rope, F.

40 G designates a similar pulley mounted beneath the draw, and under which runs the rope F. A swivel-clamp, h, connects the lower end of rope F to a rod, H, and this rod leads to the center of the draw, at which point a suitable power or hand windlass is placed.

45 Upon the outer end of shore-span B are mounted two guides, I, held in vertical position and parallel with each other by a frame, J.

K designates a grooved pulley, which is

mounted upon frame J; and K' designates a similar pulley, mounted beneath the span B. A rope, L, runs over pulley K, and a rope, 55 L', runs under pulley K' and thence to the gate or signal upon the shore-span.

M designates a slide, which works upon guides I and in the face of which is formed a horizontal groove, m. The lower end of rope 60 L is attached to said slide, while the upper end of rope L' is likewise attached to the same. The slide M is exactly counterbalanced by a weight, W, attached to the upper end of rope L.

65 N designates a slide working upon the guides C and having on its face a horizontal tongue or rib, n, to enter groove m of slide M. The rope F is attached at its outer end to slide N.

I have not shown any form of windlass nor 70 any gates or signals, as such devices may be of any suitable or preferred character.

From the above description it will be seen that when the draw is to be opened the slide N is raised by power at the center of the draw 75 and raises slide M, thus closing the gate or operating the signal. The draw is now opened and the tongue of slide N moves freely out of the groove of slide M. While the draw is open, the slide M is held firmly in raised condition by counter-weight W, so that the gate or signal is maintained in proper warning position. When the draw is closed, the tongue n enters groove m, and the weight of slide N overcomes the equilibrium between slide M 80 and weight W, so that by paying out from the windlass the slides will descend and the gate be opened or the signal moved back into normal position.

85 It will be observed that the sides of the groove m are beveled off, so that said groove is wider at its ends than at its center. This is to compensate for any variations in level between the draw and shore-span, in order that the tongue may always enter the groove.

90 Having thus described my invention, I claim as new and desire to secure by Letters Patent—

1. An improved attachment for operating gates, &c., upon draw-bridges, consisting of two members engaging in the line of movement of the draw and operating together at right angles to the line of engagement to actuate the gate or signal, as described.

100 2. The combination of a slide moving ver-

tically upon the draw, of a slide moving similarly upon the fixed span, and connections for operating said slides, substantially as set forth.

3. The combination, with the draw and fixed 5 span, of the counterweighted grooved slide and the tongued slide, and the connections between the latter and a windlass, as specified.

4. The combination, with the draw A, having the guides C and frame D, the pulleys E

G, rope F, and slide N, having tongue n, of 10 the shore-span B, having guides I, frame J, pulleys K K', ropes L L', counter-weight W, and slide M, having groove m, as and for the purposes described.

WILLIAM D. BULLOCK.
